PRESSURE TRANSFORMER

Maurice Monoyer, Brussels, Belgium

Application April 8, 1947, Serial No. 740,189
In Belgium April 16, 1946

5 Claims. (Cl. 103—51)

1

The invention relates to the combination of an hydraulic pressure transformer with a low pressure pump and in particular with a centrifugal pump for the purpose of continuously delivering a liquid at high pressure.

An object of the invention is to provide a new combination of elements which is adapted to supply a continuous delivery of liquid at high pressure when supplied with driving liquid at a low pressure from a centrifugal pump.

Another object of the invention is to provide a combination of elements in which a centrifugal pump is supplying liquid at low pressure to a pressure transformer through a rotating distributor for driving differential double-acting pistons moving in low pressure cylinders having equal diameter while the high pressure cylinders located at each end of each low pressure cylinder have diameters different from one another.

Still another object of the invention is to provide a combination of a centrifugal pump with a pressure transformer in which the high pressure cylinders are alternately located around the rotating distributor so that the high pressure cylinders of a certain diameter are located between high pressure cylinders of different diameters.

Still another object of the invention consists in providing on the discharging pipe an automatic device for controlling the pressure of the exhausted liquid which comprises a chamber having two valves, one of which moves under the joint action of the pressures of the driving fluid and of the discharged fluid while the other is actuated under the action of the driving fluid only.

With these objects and other purposes as shown below, the invention will be described and more particularly pointed out in the following specification, drawings and claims.

In the drawings:

Figure 1 is a diagrammatic sectional view showing the principle of operation of the combination according to the invention.

Figure 2 is a diagrammatic sectional view particularly illustrating an automatic device on the discharging pipe.

Figure 3 is a diagrammatic sectional view showing a combination in which the high pressure cylinders have different diameters.

Figure 4 is a transversal sectional view through a combination with six differential pistons, wherein the high pressure cylinders of different diameter are alternately located around the distributor.

Figures 5, 6 and 7 are sectional views through the automatic device, the latter being respectively at rest, at the time of being actuated by the liquid at low pressure and at the time of being actuated at high pressure.

Figure 8 is a view partly in section and partly in perspective for illustrating the speed reducing device.

2

In the figures like reference characters relate to like parts.

According to Figure 1, a pump 1 draws liquid from a tank 2 and delivers it at low pressure through a pipe 3, which divides into two branches 6 and 7, a rotary distributor 4, which is actuated by a pulley 5 and which puts these branches into communication with one or the other of the faces of a piston 10, freely sliding in a cylinder 12. Two other pistons 11 and 11a connected to the piston 10 slide in two other cylinders 13 and 13a. 14 and 15 are passages through the distributor 4, communicating with the pipes 7 and 6 respectively.

Assuming that the passage 15 of the distributor 4 is open, the passage 14 being closed, then the liquid arriving from the pump 1 through the pipe 6 traverses the distributor 4 and goes into a chamber 12a in the cylinder 12, so as to act upon the face 9 of the piston 10, thus urging the differential piston 10—11—11a towards the left and producing a partial vacuum in the compression chamber 16. The chamber 12a is filled with liquid coming from the pipe 6. The same applies to the chamber 16, which is filled with liquid by a pipe 17, by which the two chambers 12a and 16 communicate with one another if a valve 18 located on this pipe is open. When the chamber 16 is full, the distributor 4 continuing its course opens the passage 14, thus enabling the liquid coming from the pipe 7 to enter the chamber 12b.

The differential piston 10—11 returns towards the right, compressing in the chamber 16 the liquid contained therein, which closes the valve 18 and opens a valve 19, which admits the liquid to a channel 20, leading to the service pipe 21. The liquid contained in the chamber 12a returns to the tank 2 by a pipe 22 through a separate passage, not shown, provided in the distributor 4, which communicates with a pipe-line, not shown, and the cycle recommences with the opening of the port 15, the closing of the port 14, and the opening of the ports, not shown, that enable the fluid contained in the chamber 12b to return to the tank 2.

Figure 2 represents an application of the invention. In this figure, two differential pistons 21 and 22 are represented, moving in cylinders 29 and 39 respectively. A distributor 25 turning in a casing 26 is actuated through the medium of a pulley 24 by a motor 23. In the casing 26, an annular crown-member 27—27a is constructed in such a manner that the fluid can pass into the cylinders 29 and 39 on to one or the other face of the pistons 21 and 22 according to the position of ports 31 and 32 provided in the distributor 25.

The centrifugal pump 1 drawing water from the tank 2 feeds through the pipe 3 an annular cavity 27—27a provided in the casing 26. Figure 2 represents the apparatus at the time when the distributor is so placed that the annular

crown-member 27—27a enables the fluid to pass from the port 32 on to the face 34 of the piston 21 and from the port 31 on to the face 33 of the piston 22 in the direction of the arrows. The fluid is also directed into compression chambers 37 and 38 through pipes 35 and 36 by opening valves 39 and 40.

The piston 21 is therefore urged upwards and the piston 22 downwards. This movement first has the effect of delivering the fluid contained in the portions 45 and 46 of the cylinders 29 and 30 through pipes 43 and 44 and through a central pipe-system 47 to the tank 2, and then of compressing the fluid that had been admitted into the compression chambers 48 and 49 during the preceding stroke, thus compelling the valves 50 and 51 to open and to allow the fluid to pass into a pipe-system 52—53—54—55, the end 55 of which leads to an automatic device 56, which feeds the service pipe 57.

Since the distributor 25 continues to turn, the same cycle recommences for the other faces of the piston, thus enabling the pipe system 57 to be continuously fed with compressed fluid through the automatic device 56.

It need hardly be said that the principle of the apparatus hereinbefore described can also be applied to pressure-reducing apparatus especially intended for liquids, which apparatus, receiving a high-pressure liquid, uses the driving power of the said liquid in order to deliver a greater volume of another liquid at low pressure.

If the system be used as a press pump, the various phases involved may be automatically effected, namely:

(1) Approach stroke of the piston of the pump (low pressure).

(2) Pressure stroke (at high pressure).

Automatic working is effected by interposing an automatic device 56 (Figure 2), as hereinbefore stated. A pipe system 58 branched on the supply pipe 3 of the centrifugal pump 1 is connected to the device 56, and the delivery of this pump constitutes the approach delivery at low pressure.

At the beginning of a pressing operation, the pressure in the pipe system 57 which leads towards the press is zero, and the device 56 is in the stoppage position (see also Figure 5), the valves 59 and 60 pressing on their respective seats.

In order to lower the piston of the press, an operation which is effected at low pressure, the centrifugal pump 1 delivers into the pipe system 58, and raises the valve 59, and the fluid travels towards the service pipe 57 (see also Figure 6). The valve 60 is kept on its seat by the action of a strong adjustable spring pressing upon this valve through the medium of a piston 61. The pipe system 55 is therefore shut off by the valve 60, and hence there is established in the pipe system 52—53—54—55 a pressure equal to the maximum pressure which is capable of being produced by the small pistons 62, 63, 64 and 65. This pressure being attained, the pistons 62, 63, 64 and 65 are immobilised by the equilibrium which is established between the driving effort on the large pistons 21 and 22 and the force resisting the said pistons. Consequently, the pistons are practically immobilised at the very beginning of the pressing operation, since only a few strokes of these pistons are required in order to effect the equilibrating pressure in the pipe system 52—53—54 and 55,

and hence the pressure-transformer is for the moment out of service and does not use the delivery of the pump 1. This delivery therefore passes entirely through the pipe system 58 the service pipe 57 by raising the valve 59, and effects the low-pressure approach stroke of the press connected to this service pipe.

As soon as this stroke is terminated, which happens when the force on the piston of the press increases, the delivery of the pump 1 stops and the pressure in the pipe-system 58—57 therefore increases up to the maximum value which the centrifugal pump can attain.

This feature has two results:

(1) The valve 59 is closed by the action of its return spring, since the delivery is zero; and

(2) The pressure attained in the pipe 57 is also transmitted to the inside of the apparatus 56, that is to say, to a chamber 62, which communicates with the pipe 57.

This pressure is just the pressure which, acting upon the piston 61, is capable of overcoming the tension of the adjustable spring 63. Hence, the piston 61 moves, compressing the spring 63 and liberating the valve 60, which opens. We then have the position of Figure 7, that is to say, the valve 59 is closed and the valve 60 is open. Owing to the opening of the latter valve, the pipe system 54 (which was subjected to high pressure as indicated at the beginning of this description) is put into communication with the chamber 62 and with the pipe system 57, which are both at low pressure. Consequently, the pressure in the pipe system 54 falls so as to equal that of the pipe 57 and the chamber 62.

At this junction the pressure-transformer begins to function. Indeed, the pressure in the pipe system 52—53—54—55 having fallen, the small pistons 62, 63, 64 and 65 are no longer subjected to a force capable of counteracting the force acting upon the pistons 21 and 22, and the movement of the said pistons is produced while effecting the discharge of the delivery occasioned by the pistons 62, 63, 64 and 65 through the manifold 52—53—54—55 towards the pipe system 57 and passing through the valve 60, which is raised.

The second stage of the press operation now begins, that is to say, the stage of the high-pressure stroke. This stroke will continue until the maximum pressure has been reached in the pipe system 57, which pressure will be that causing the pistons 62, 63, 64 and 65 to be immobilised as hereinbefore explained.

When the press operation is completed, the pipe system 57 is isolated from the press by a cock placed on the said press. This pipe system 57 therefore remains at maximum pressure, thus keeping the pistons 62, 63, 64 and 65 immobilised.

At the time of a fresh press operation, the pipe system 57 is again put into communication with the press (the pressure of which has been previously reduced to zero), which has the effect of returning the valve 60, to its seat through the action of a spring 63, which is no longer balanced by the force on the piston 61, and the same cycle recommences.

It is possible further to increase the effectiveness of such a hydraulic-pump press by providing two series of pistons of different cross sections, thus enabling an intermediate pressure to be created, which may be called "moderate pressure."

The automatic apparatus 56 of Figure 2 is then constructed in such a manner as to have two valves such as 60 and two springs such as 63 of different stiffness so as to enable the following operations to be successively put into service:

- (1) Direct delivery of the centrifugal pump for the approach stroke at low pressure;
- (2) Medium delivery at moderate pressure by the first series of pistons;
- (3) Small delivery at high pressure by the second series of pistons.

This automatic apparatus is, in this case, the apparatus represented at 70 in Figure 3.

It will first of all be noticed that the pipes 35 and 36 in Figure 2 are replaced in Figure 3 by tubes or ducts 84a, 85a, 86a, 87a, which are inside pistons 84, 85, 86 and 87, provided with valves 84b, 85b, 86b and 87b respectively at their ends, and communicating with the chambers of the pistons 82 and 83 through lateral openings, these tubes thus enabling the part of the fluid to be compressed to enter the compression chambers 88, 89, 90 and 91 so as to be compressed therein.

In Figure 3, 71 is a retaining or non-return valve located at the low pressure, 72 is a valve loaded with an adjustable spring for the mean-pressure delivery, and 73 is a valve loaded with an adjustable spring for the high-pressure delivery.

The mode of operation is identical with that of the apparatus illustrated in Figure 2, with the modification that when the low-pressure delivery terminates, the valve 72 opens under the action of the pressure on the piston 74, and, when this medium-pressure delivery terminates, the valve 73 opens under the action of the new pressure acting upon the piston 75, and does this while the valve 72 is closing through the action of its small return spring.

It need hardly be said that, according to circumstance, it is possible to provide other intermediate deliveries and pressures by using for each of them a different series of valves, pistons and springs.

Figures 3 and 4 show a form of construction of a press pump so arranged as to operate the centrifugal pump and the distributor by the same source of power.

The functioning is as follows: A centrifugal pump 76 sucks the liquid from a tank 77 forming a stand for the group, through a filter 78, and discharges the said liquid at a low pressure through channels 79 into an annular chamber 80. A distributor 81 effects the successive distribution of the liquid between groups of pistons 82 and 83, which are thereby actuated with a reciprocating motion, as are also the medium-pressure pistons 84 and 85, and the high-pressure pistons 86 and 87, which discharge into chambers 88, 89, 90 and 91 leading to manifolds 92 and 93.

The medium-pressure pistons 84 and 85, the cross-sections 1 area of which is greater than that of the pistons 86 and 87, produce a final pressure which is lower than that of the latter pistons, but the quantity delivered by the former pistons is larger. Hence, with the automatic adjusting device 70, the following stages occur for one press operation:

(1) Approach stroke, during which the centrifugal pump delivers directly through the manifold 94, the pistons 84, 85, 86 and 87 being immobilised;

(2) Moderate delivery, at moderate pressure, through the manifold 92 corresponding to the pistons 84 and 85 which function alone, the two pistons 86 and 87 (see Figures 3 and 4) remaining stationary;

(3) Small delivery at high pressure through the manifold 93 corresponding to the two pistons 86 and 87 (Figures 3 and 4), which function alone, the pistons 84 and 85 being automatically immobilised because they cannot overcome the pressure established in the manifold 92, which is greater than the pressure that can be produced by the pistons 84 and 85.

An electric motor 95 with a vertical shaft is the sole source of motive power for the unit, and the distributor 81 is set in motion by means of a speed-reducing device with gear wheels 96, itself driven by the vertical spindle of the centrifugal pump.

Figure 8 gives details of the speed-reducing device and the distributor. The speed-reducing device is constructed as follows: A main shaft 97, connecting the motor to the centrifugal pump, carries a pinion 98, which engages with two toothed wheels 99 and 100. These two toothed wheels are mounted upon spindles 101 and 102, which are fixed to a plate 103 which is rigid with a distributor 81. Moreover, these spindles 101 and 102 carry two small pinions 105 and 106 driven by the wheels 99 and 100 and engaging with an internally toothed crown wheel 107, which remains fixed.

The rotation of the pinion 98 rotates the plate 103 and consequently the distributor 81, in the same direction but at a very much reduced speed, since the latter speed is a function of the ratio between the numbers of teeth on the pinion 98 and on the toothed wheels 99 and 100 on the one hand, and of the ratio between the numbers of teeth of the satellite pinions 105 and 106 and the ring of internal teeth 107 on the other hand.

The distributor 81 comprises a series of passages 108 and 109 which traverse the wall, and of cells 110 and 111, which have no communication with the inside of the distributor sheath 81. When this distributor turns, one cell 110 puts an annular channel 112-112a, which is under pressure, into communication with the lower face of the piston 83 through a channel 114, while the upper face of the piston 83 is put into communication with the emission of liquid through a channel 115, the passage 108 and the interior of the distributor, and leaves the latter at the top in the direction of the arrow X.

It will be seen, therefore, that the distributor, through its rotary movement, successively puts each of the faces of the pistons 82 and 83 (Figure 3) into contact with the driving fluid and thus effects the reciprocating movements of the said pistons.

It will be obvious that the same process happens over the whole of the series of pistons, so that the delivery occasioned by the pistons is continuous. This is due to a careful arrangement of the channels and ports over the distributor.

In the constructions indicated in Figures 1, 2 and 3, the part of the fluid compressed to a high pressure is drawn from the driving fluid at low pressure. Nevertheless it need hardly be said that these two fluids may be different, and that it is possible, for instance,

(1) To use an air or gas driving-fluid and to compress a liquid;

- (2) To use a driving liquid in order to compress air or any gas;
- (3) To use air or any gas in order to compress another gas; or
- (4) To use any liquid in order to compress another liquid.

All these constructions differ merely to a very small extent from the constructions illustrated, except with regard to the feeding of the pistons at high pressure, which has to be separate from the low-pressure driving fluid whenever two different fluids are used.

The low-pressure feed pump may be omitted if use be made of a driving fluid at low pressure drawn from an existing supply pipe (water from a hydraulic main or the like).

In this case the rotation of the rotary distributor is effected by means of a separate small motor, or by any other device, turbine for example, using the driving fluid.

What I claim is:

1. In a combination with a centrifugal pump of a pressure transformer comprising a plurality of low pressure cylinders, a high pressure cylinder at each end of each low pressure cylinder, a differential piston moving in each of said cylinders, a rotating distributor located between said cylinders for alternatively supplying fluid from said centrifugal pump to the opposite sections of the low pressure cylinders and to the high pressure cylinders, an external means for driving said rotating distributor, a discharging pipe, an automatic device located on said discharging pipe for controlling the pressure of the exhausted fluid, said automatic device comprising a chamber provided with two valves, one of which moving under the joint action of the pressures of the driving fluid and of the discharged fluid, the other moving under the action of the driving fluid only.

2. In a combination with a centrifugal pump of a pressure transformer comprising a plurality of low pressure cylinders having the same diameters, a high pressure cylinder at each end of each low pressure cylinder, some high pressure cylinders having equal diameters, a differential piston moving in each of said cylinders, a rotating distributor located between said cylinders for alternatively supplying fluid from said centrifugal pump to the opposite sections of the low pressure cylinders and to the high pressure cylinders, an external means for driving said rotating distributor, a discharging pipe, an automatic device located on said discharging pipe, said automatic device comprising a chamber provided with two valves, one of which moving under the joint action of the driving fluid and of the discharged fluid, the other moving under the action of the driving fluid only.

3. In a combination with a centrifugal pump of a pressure transformer comprising a plurality of low pressure cylinders having the same diameters, a high pressure cylinder at each end of each low pressure cylinder, half the number of the high pressure cylinders having diameters different from those of the other half, a differential piston moving in each of said cylinders, a rotating distributor located between said cylinders for alternatively supplying fluid from said centrifugal pump to the opposite sections of the low pressure cylinders and to the high pressure cylinders, an external means for driving simul-

taneously said rotating distributor and said pump, a discharging pipe, an automatic device located on said discharging pipe, said automatic device comprising a chamber provided with two valves, one of which moves under the joint action of the pressures of the driving fluid and of the discharged fluid and the other under the action of the driving fluid only.

- 4. In a combination with a centrifugal pump of a pressure transformer comprising a plurality of low pressure cylinders, a high pressure cylinder at each end of each low pressure cylinder, a differential piston moving in each of said cylinders, a rotating distributor located between said cylinders for alternatively supplying fluid from said centrifugal pump to the opposite sections of the low pressure cylinders and to the high pressure cylinders, an external means for driving said rotating distributor, a discharging pipe, an automatic device located on said discharging pipe for controlling the pressure of the exhausted fluid, said automatic device comprising a chamber provided with two valves, one of which moving under the joint action of the pressures of the driving fluid and of the discharged fluid, the other moving under the action of the driving fluid only, said low pressure cylinders having equal diameter and said high pressure cylinders having different diameters.
- 5. In a combination with a centrifugal pump of the pressure transformer comprising a plurality of low pressure cylinders, a high pressure cylinder at each end of each low pressure cylinder, a differential piston moving in each of said cylinders, a rotating distributor located between said cylinders for alternatively supplying fluid from said centrifugal pump to the opposite sections of the low pressure cylinders and to the high pressure cylinders, an external means for driving said rotating distributor, a discharging pipe, an automatic device located on said discharging pipe for controlling the pressure of the exhausted fluid, said automatic device comprising a chamber provided with two valves, one of which moving under the joint action of the pressures of the driving fluid and of the discharged fluid, the other moving under the action of the driving fluid only, said low pressure cylinders having equal diameter and said high pressure cylinders having different diameters.
- 6. In a combination with a centrifugal pump of the pressure transformer comprising a plurality of low pressure cylinders, a high pressure cylinder at each end of each low pressure cylinder, a differential piston moving in each of said cylinders, a rotating distributor located between said cylinders for alternatively supplying fluid from said centrifugal pump to the opposite sections of the low pressure cylinders and to the high pressure cylinders, an external means for driving said rotating distributor, a discharging pipe, an automatic device located on said discharging pipe for controlling the pressure of the exhausted fluid, said automatic device comprising a chamber provided with two valves, one of which moving under the joint action of the pressures of the driving fluid and of the discharged fluid, the other moving under the action of the driving fluid only, said low pressure cylinders having equal diameter and said high pressure cylinders having different diameters, said high pressure cylinders being arranged around the rotating distributor so that the high pressure cylinders having a certain diameter are located between the high pressure cylinders of a different diameter.
